Primary Examiner — Darcey E Gottschalk*Assistant Examiner* — Bailey M Knotts(74) *Attorney, Agent, or Firm* — Weiss & Moy, PC;
Jeffrey D. Moy(57) **CLAIM**

The ornamental design for a hanging light fixture as shown and described.

DESCRIPTION

FIG. 1 is an elevated side perspective view of a hanging light fixture, showing our new design;

FIG. 2 is a front view thereof;

FIG. 3 is a rear view thereof;

FIG. 4 is a right-side view thereof;

FIG. 5 is a left side view thereof;

FIG. 6 is a top view thereof; and,

FIG. 7 is a bottom view thereof.

In the drawings, the broken lines depict portions of the hanging light fixture that form no part of the claimed design.
